UNITED STATES PATENT OFFICE.

WALTER S. COE, OF BROOKLYN, NEW YORK, ASSIGNOR TO MERGENTHALER LINOTYPE COMPANY, A CORPORATION OF NEW YORK.

LINOTYPE-MACHINE.

No. 652,822.

Specification of Letters Patent.

Patented May 7, 1907.

Application filed March 2, 1907. Serial No. 360,186.

To all whom it may concern:

Be it known that I, WALTER S. COE, of Brooklyn, county of Kings, and State of New York, have invented a new and useful Improvement in Linotype-Machines, of which the following is a specification.

My invention has reference to linotype machines of the character represented in Letters Patent of the United States No. 436,532 and has reference particularly to the automatic devices, commonly known as tripping devices, for throwing the main driving clutch out of action in the event of the "first-elevator" failing to lower the composed line of matrices to the proper position in front of the mold.

In this class of machines the composed line of matrices, containing the characters which are to appear on one printing slug or linotype, is suspended in the "first-elevator," so called, and by this elevator it is lowered to the casting position directly in front of the horizontal, slotted mold.

The mold is mounted in a vertical disk, rotated intermittently to carry the contained slug from the horizontal casting position, to the vertical ejecting position. The mold-disk has a horizontal or face-wise movement to and from the matrix line, in order to withdraw the type characters on the slug from the matrices, preparatory to the rotation of the disk. The clutch controlling devices include, at the front of the machine, an upright bar movable both vertically and horizontally. When the first-elevator descends to the proper position it pushes this bar down to such a point that the mold-disk and mold may advance to the casting position without affecting the bar or clutch—the latter being held normally in action by a spring. If, however, the first-elevator fails to descend a sufficient distance to properly locate the matrices the bar is left in an elevated position and so that it will be acted upon, and moved by, the advancing mold, the bar thus moved acting in turn to throw the clutch out of action and arrest the movement of the casting mechanism.

In the machine of the original patent there was one mold only in the disk, but in modern machines it is a common practice to provide the disk with two or three molds of different sizes, any one of which may be brought into action at will. In such case it will sometimes

happen that when one mold is in the ejecting position, and the first-elevator raised, another mold will be in position to stop the machine—a result which is not desired.

The present invention is designed to overcome this difficulty, and consists in means to prevent the clutch tripping devices from acting when the first-elevator is raised.

In the accompanying drawings I have shown my invention applied to a commercial linotype machine of the present day, the parts being all of the ordinary construction, except as to the safety devices hereinafter described.

Referring to the drawings; Figure 1 is a perspective view looking against the front face of the mold-disk and molds, with the first-elevator and adjacent parts in vertical section. Fig. 2 is a side elevation of the parts shown in Fig. 1, the mold-disk and certain other portions being shown in vertical section. Fig. 3 is a perspective view looking from the rear and showing the safety devices and their connection with the clutch.

Referring to the drawings; A represents the rigid frame work of the machine, B the vertical disk, having a series of slotted molds, C secured therein, this disk being mounted to rotate intermittently on a central axis or support, D, which is movable horizontally forward and backward to carry the molds against the line of matrices, E, which is suspended temporarily in the slotted upper end of the first elevator, F, guided to move upward and downward in the main-frame, for the purpose of lowering the matrices from the elevated position shown in Fig. 2 to the casting level, in front of that mold which is for the time being in use, as shown in Fig. 1.

G is the automatic clutch controlling or tripping bar, having its upper end mounted to slide vertically in the main-frame and its lower end mounted to swing forward and backward to a limited extent. This bar, G, is urged constantly upward by a spring, H, and at its lower end it bears against one end of a lever, I, centrally pivoted in the main-frame. The lever I bears at the opposite end against a sliding bar, J. This bar, J, is in turn connected at its rear end to an elbow lever, L, which controls the normally engaged main driving clutch, M, from which motion is communicated to the entire casting

mechanism. The arrangement is such that when the lower end of the bar, G is pushed forward in the manner explained below it will throw the clutch out of action and stop the casting mechanism.

5 N represents a horizontal slide mounted in the main-frame between the mold-disk and the clutch controlling bar, G, which latter is provided with a lip or shoulder, g.

- 10 In the normal position of the parts the bar G is raised so that its upper end projects above the top of the main-frame. At this time the lip, g, stands directly in front of the slide, N, so that if when the mold-disk is moved forward to the casting position there happens to be a mold opposite the slide, N, it will push the latter forward and cause it in turn to push the lower end of the bar, G, forward, thereby tripping the clutch and 15 improperly stopping the machine.

When the first elevator, F, descends with the matrix-line it acts upon the upper end of the rod, G, and carries the same downward, and when the line arrives at the proper casting level, and not before, the lip, g, will be carried below the slide, N, so that although the slide is moved forward by the advancing mold it will miss the lip, g, and fail to move the bar, G, and consequently the action of 20 the machine will continue. It may happen, however, that while one of the molds is in the vertical or ejecting position and the first elevator, F, and bar, G, raised, another mold may be presented opposite the slide, N; so that the forward movement of the mold and disk—which occurs just before the ejection—will cause the machine to be improperly stopped.

- 25 So far as described the parts are of substantially the same construction and arrangement as in the original machine; and in the absence of my new parts the additional molds used would cause improper stoppages as explained. To overcome this difficulty I 30 provide a lever, o, pivoted to the main-frame, with one end arranged to act upon and depress the bar, G, and the opposite end arranged to be acted upon by a projection, f, on the first elevator. The arrangement of 35 the parts is such that whenever the first elevator is raised to its uppermost position it will cause the lever, o, to depress the bar G, so that it cannot be moved by the slide, N, to disengage the clutch.
- 40 55 It will be observed that in the arrangement shown the elevator, F, serves to depress the clutch-tripping bar, G, and prevent its action, not only when the elevator and matrices are fully down to the casting position, but 50 also when the elevator and matrices approach their uppermost position. Thus it is

that the automatic stoppage of the machine is effected, and effected only when there is a failure to lower the matrix-line to the proper casting level, regardless of the number of 65 molds in the disk.

I believe it to be wholly new to combine with the driving-clutch of a linotype machine means actuated by the molds or mold disk to throw the driving-clutch out of action 70 only when the matrix-line is slightly above the casting position, regardless of the number of molds used in the disk. In other words, I believe it to be wholly new to provide a clutch-tripping device actuated by the 75 molds and combined with means to prevent its operation in the event of a mold acting thereon, when the first elevator is raised—as it is when any mold is in the ejecting position.

80 Having described my invention, what I claim and desire to secure by Letters Patent is:—

1. In a linotype machine, and in combination, a main driving-clutch, a clutch-tripping device, a vertically movable first elevator, and means through which the elevator acts when fully down, and also when fully elevated, to prevent the operation of the tripping device.

2. In a linotype machine, the mold carrying disk movable face-wise, the slide N, and the clutch controlling bar G, in combination with the lifting spring H, the first elevator acting directly to depress bar G, and the lever o, acting to depress the bar when the elevator is raised.

3. In a linotype machine, a main driving clutch normally engaged, a mold movable from the casting to the ejecting position, and an elevator for carrying the matrix-line to the mold, in combination with clutch tripping devices controlled by the elevator and operative only when the matrix-line is away from the casting position.

4. In a linotype machine, a mold disk provided with plural molds and having both rotary and face-wise movements, in combination with a driving clutch, an elevator to present the matrix-line to the operative mold, a clutch-tripping device actuated by the advance of the mold disk, and means to prevent said action of the tripping device when the elevator is near its uppermost position.

105 In testimony whereof I hereunto set my hand this sixth day of February, 1907, in the presence of two attesting witnesses.
